(57) **CLAIM**

The ornamental design for a disc recorder, as shown and
described.

DESCRIPTION

FIG. 1 is a perspective view of a disc recorder showing my
new design;

FIG. 2 is a front elevational view thereof;

FIG. 3 is a reference rear elevational view thereof;

FIG. 4 is a reference left side elevational view thereof;

FIG. 5 is a reference right side elevational view thereof;

FIG. 6 is a reference top plan view thereof; and

FIG. 7 is a reference bottom plan view thereof.

FIG. 8 is another embodiment of a perspective view of a disc
recorder showing my new design; and,

FIG. 9 is a front elevational view thereof.

The broken lines are for illustrative purposes only and form
no part of the claimed design.
